(57) **CLAIM**

The ornamental design for a laser distance measurement device, as shown and described.

DESCRIPTION

This application contains subject matter related to the following co-pending U.S. design patent application:

Application Ser. No. 29/393,485, filed Jun. 6, 2011 and entitled “Laser Distance Measurement Device.”

FIG. 1 is a left, front perspective view of a laser distance measurement device according to our design;

FIG. 2 is a front view thereof; and,

FIG. 3 is a front, top perspective view thereof.

The broken lines are for illustrative purposes only and form no part of the claimed design.

1 Claim, 3 Drawing Sheets

FIG. 1

FIG. 2

FIG. 3
